[57] CLAIM

The ornamental design for a child's pillow, as shown and described.

DESCRIPTION

FIG. 1 is a perspective view of a child's pillow taken from above the right front corner;

FIG. 2 is a top view of the child's pillow of FIG. 1;
FIG. 3 is a side view of the child's pillow of FIG. 1 taken from its left side;

FIG. 4 is a view of the child's pillow taken from the rear; and,

FIG. 5 is a view of the underside of the child's pillow.
The stippled shading represents conventional fabric and is understood to extend uniformly throughout the areas represented.
